CARTON

Clarence J. Alfred, Orange, N. J., assignor to The
American Sugar Refining Company, New York,
N. Y., a corporation of New Jersey

Application November 26, 1934, Serial No. 754,711

11 Claims. (Cl. 229—17)

This invention relates to cartons used for the distribution of sugar, salt and similar commodities, and is concerned more particularly with a carton of novel construction which is provided with means which can be readily manipulated to produce an opening through which the contents of the carton can be discharged, and thereafter to close the opening, if desired.

Cartons having pouring openings have been made heretofore in many different forms, but those with which I am familiar are not wholly satisfactory, particularly for distribution of finely divided materials, such as granulated or powdered sugar. The objections to the prior cartons are either that they are complicated and expensive to manufacture or to fill and seal or have closure means for the pouring opening which are difficult to operate, or else that the closure means do not provide an effective seal which will prevent loss of contents in handling.

The present invention is accordingly directed to the provision of a simple inexpensive carton particularly suited for the distribution of sugar and similar materials, the new carton having a pouring opening and a closure means therefor which provide a strong seal capable of preventing leakage, even though the carton is roughly handled, and which can be easily operated to expose the opening, whenever that is desired, and also to close the opening, if only a portion of the contents is to be removed at a time.

The new carton is provided with the usual closing flaps secured together by adhesive, and at its discharge end, the carton has a pair of inner flaps folded inward over the end of the carton and having an opening therethrough which is normally closed by an intermediate flap which overlies the inner flaps. The intermediate flap has a movable section in registry with the opening through the inner flaps, and this section may take the form of a tab which may be displaced to uncover the opening when the carton is to be emptied and may be replaced, if desired, to close the opening after only a part of the carton contents have been removed. The tab section extends slightly beyond the edge of the opening and overlies the inner flaps, the latter thus providing a seat which serves to support the tab in position. The seat also tends to prevent the tab from being forced inwardly through the opening in the operations of initially removing the tab and of replacing it. An outer flap overlies the intermediate flap and this outer flap is provided with a movable section which is preferably hinged and is secured in position normally over-

lying the tab by readily destructible means. The hinged section, while held firmly in place under normal conditions and thus with the tab providing an effective seal for the opening, does not lie in as close contact with and is not secured as effectively by the adhesive to the surface of the intermediate flap, as the remaining portions of the outer flap. In consequence, the hinged section can be readily swung out of place to expose the tab beneath it; and when the tab is likewise swung out of its normal position, the contents of the carton are exposed through the opening in the inner flaps and may be poured out through that opening and over the surface of the tab which serves to direct the stream of contents and acts in the manner of a spout. If only a portion of the contents of the carton is to be discharged, the pouring opening may be reclosed by replacing the tab and the hinged section in their original positions.

For a better understanding of the invention, reference may be had to the accompanying drawing, in which

Figures 1, 2 and 3 illustrate successive steps in the opening of the new carton and the discharge of its contents;

Figures 4 and 5 are views in perspective illustrating the sealing of the discharge end of the new carton;

Figure 6 is a view similar to Figures 4 and 5, but showing only a portion of the carton with the pouring end fully sealed;

Figure 7 is a top plan view of the end of the carton shown in Figure 6;

Figures 8 and 9 are plan and end views, respectively, of a pressure plate used in sealing the carton;

Figure 10 is a plan view of the carton with the hinged section of the outer flap removed and showing a modified form of intermediate flap;

Figure 11 is a sectional view on the line 11—11 of Figure 10;

Figure 12 is a top plan view of the carton with the hinged section of the outer flap removed and showing a second modified form of intermediate flap;

Figure 13 is a fragmentary plan view similar to Figure 12 and showing another modified form of intermediate flap.

Referring to the drawing, the new carton is illustrated in a form suitable for distribution of sugar in granulated form and the carton is made of a blank of paper board folded and secured together lengthwise in the usual way to form a generally rectangular body 20. At the bottom

end of the carton which is to remain permanently sealed are inner flaps 21 which, when folded inwardly over the end of the carton lie with their edges in proximity. Extending beyond another 5 wall of the carton is an intermediate flap 22 which is to be folded over the inner flaps and secured thereto by a film of adhesive. An outer flap 23 similar to the intermediate flap 22 is then folded inwardly over the latter and secured there- 10 to by adhesive.

At the other end of the carton are inner flaps 24 constituting extensions from the opposite 15 walls of the carton and adapted to be folded inwardly over the end of the carton, as illustrated in Figure 4. A discharge opening is formed through the inner flaps, and for this purpose, the flaps may lie with their free ends in proximity and each flap may have a cut-out 25 at its free end, the two cut-outs adjoining when the flaps 20 are in folded position so as to provide a discharge opening.

Projecting beyond another wall of the carton is an intermediate flap 26 which is to be folded over upon the inner flaps and secured thereto by adhesive. This intermediate flap is provided with a movable section 27 held in place by readily 25 destructible means so that it may be swung out of position or, if desired, wholly removed. Preferably, the section has the form of a tab which 30 has a free end 28 defined by a curved slit, while the sides of the tab section are connected to the remainder of the intermediate flap by lines of perforation 29. Preferably, the perforated lines 35 terminate short of the line 30 along which the intermediate flap is joined to the wall of the carton and on which the flap is folded inwardly. As shown in Figure 7, the tab section is preferably of such proportions that it overlies and extends beyond the edge of the pouring opening so 40 that the free end of the tab section is supported from beneath by a portion of the inner flaps lying adjacent the pouring opening and providing a seat 28a. In the construction illustrated, the slit at the end of the tab partially overlies the opening through the inner flaps but, if desired, the tab or the seat portion of the inner flaps may be 45 so constructed that solid portions of the inner flaps lie beneath the entire slit.

Extending beyond another wall of the carton 50 is the outer flap 31 which is to be folded inwardly to overlie the intermediate flap and be secured thereto by adhesive. The outer flap has a movable section 32 which can be either swung out of position or wholly removed. Preferably, the section 55 is hinged and it extends outwardly from a scored or weakened line 33 lying inward from and parallel to the free edge 34 of the flap, the sides of the hinged section being connected to the remainder of the flap by perforated lines 35. In the inwardly folded position of the outer flap 31, the hinged section 32 wholly overlies the tab 27 and the pouring opening.

The operations of discharging the contents 60 through the pouring opening of the carton are illustrated in Figures 1, 2 and 3 and the first operation (Fig. 1) is that of raising the hinged section out of the plane of the outer flap so as to expose the tab 27. For this purpose, the user inserts his fingernail under the free edge of the 65 hinged section and raises it by rupturing the perforated connections 35. When the hinged section has been raised to the position shown in Figure 1 to expose the tab 27, the user lifts the free end of this tab with his fingernail and bends it outwardly, thus exposing the opening through

the inner flaps. The contents of the carton may then be poured through the opening over the surface of the tab and the latter serves to direct the stream of contents somewhat in the manner of a spout.

In order that the hinged section on the outer flap may be readily raised therefrom to expose the tab in the intermediate flap, I secure the flaps together by means which weakens the effect on the under surface of the hinged section of the film of adhesive which secures the outer and intermediate flaps together. In the sealing operation, the flaps at the pouring end of the carton are secured together first, and for this purpose, the carton is mounted on a block, on the end of which is mounted a pressure plate 36. This plate has the same shape as the cross-section of the carton but is provided with a transverse channel 37 in its face leading to a generally rectangular recess 38. This recess has the same general shape as the hinged section 32 but is of slightly greater width and length. The carton is mounted on the block in such manner that the hinged section will be in registry with the recess in the pressure plate, and consequently when adhesive has been applied, the flaps have been folded inwardly as described, and pressure is applied to the flaps to cause the adhesive to adhere firmly to the contacting flaps, no pressure is applied to those portions of the flaps which lie in registry with the recess 38 on the plate and the effect of the adhesive on the under surface of the hinged section is diminished. At the same time, since the hinged section is not subjected to pressure tending to compress and compact the paper board and also to force the section into tight contact with the intermediate flap and thus make the adhesive effective, the section lies offset away from the remainder of the outer flap and from the surface of the intermediate flap to a slight extent, the offset being 4 sufficient, however, to permit the fingernail to be readily inserted under the edge of the hinged section. While the section is in close enough contact with the tab to reinforce the latter and hold it against distortion by the contents of the 4 carton during the handling of the latter, the relatively slight offset of the hinged section and the lessened effect of the adhesive on its under surface facilitate the swinging of the section away from the intermediate flap to expose the tab. 5

No difficulty is ordinarily encountered in raising the tab 27 to expose the pouring opening, since the tab has an end portion which is completely severed from the remainder of the intermediate flap. However, in some instances, it may be desirable to cut or shape the intermediate flap in such manner as to facilitate the raising of the tab, and various expedients may be employed for this purpose. For example, a portion of the intermediate flap adjacent the free end of the tab may be completely removed or depressed, as indicated in Figures 10 and 11 to form a recess 39 at the end of the tab in which the fingernail may be inserted to lift the end of the tab. Instead of such a recess, the intermediate flap may have 60 a slit or weakened line 40 extending to the slit which defines the free end 28 of the tab, as shown in Figure 12. With this arrangement, the portions 41 of the intermediate flap on either side of the slit 40 may be slightly depressed so that the 65 fingernail may be inserted under the end of the tab 27 to raise it. As a further modification, the intermediate flap may be formed with two slits 42 leading to the slit defining the free end of the tab. The slits 42 preferably diverge slightly and de- 70 75

fine a secondary tab 43, the free end of which lies at the free end 28 of the tab 27. In the operation of lifting the main tab 27, the secondary tab 43 is first slightly depressed and this makes accessible the end of the main tab. In depressing the portions 41 of the intermediate flap in the construction shown in Figure 12, and the secondary tab 43 in the construction shown in Figure 13, the edges 10 of the inner flaps 24 must likewise be slightly depressed but this is easy since the portion of the intermediate flap adjacent the end of the tab and the underlying portions of the inner flap are not secured together firmly by the adhesive.

15 It will be apparent from the detailed description that the new carton can be made at the same cost as an ordinary carton without the pouring opening since the closure means for the opening consist of portions of the usual flaps and do not include any additional elements. The cut-outs in the inner flaps, the tab section, and the hinged section can all be made in the production of the blank of which the carton is made and the cutting of these parts, therefore, does not involve any additional expense. The closure means are easily operated to open and close the pouring opening and the initial manipulation of the hinged section and tab is facilitated by weakening the effect of the adhesive on the hinged section 30 and by forming the tab with a free end which is fully severed from the remainder of the flap in which it is formed. At the same time, the provision of the closure means does not weaken the carton or result in leakage of the contents thereof, since the tab does not extend to the line of folding of the intermediate flap and the perforations between the tab and the remainder of the intermediate flap, therefore, lie inward from the line of folding. Also, since the free end of the 35 tab overlies a solid seat portion of the inner flaps and is held partially in place by adhesive, the free end of the tab is properly supported so that the complete severance of the free end of the tab from the remainder of the intermediate flap likewise does not result in leakage.

What I claim:

1. In a carton, the combination of a pair of inner flaps extending from opposite walls of the carton and folded inwardly at the end of the 50 carton, said flaps being cut away to provide a pouring opening, an intermediate flap extending from another wall of the carton and folded inwardly to overlie said inner flaps, said intermediate flap including a movable tab section normally overlying said opening, an outer flap extending from another wall of the carton and folded inwardly over the intermediate flap, said outer flap including a movable section normally overlying the tab and the opening, and films of adhesive between the outer surfaces of said inner flaps and the inner surface of the intermediate flap, and between the outer surface of the intermediate flap and the inner surface of the outer flap, the contact between said movable section in 55 said outer flap and the surface of the intermediate flap beneath it being substantially less than that between the remaining portions of said flaps.

2. In a carton, the combination of a pair of inner flaps extending from opposite walls of the 70 carton and folded inwardly at the end of the carton, said flaps being cut away to provide a pouring opening, an intermediate flap extending from another wall of the carton and folded inwardly to overlie said inner flaps, said intermediate flap including a movable tab section nor-

5 mally overlying said opening, an outer flap extending from another wall of the carton and folded inwardly over the intermediate flap, said outer flap including a movable section normally overlying the tab and the opening, and films of adhesive between the outer surfaces of said inner flaps and the inner surface of the intermediate flap, and between the outer surface of the intermediate flap and the inner surface of the outer flap, said movable section in the outer flap 10 lying offset upwardly from the remainder of the outer flap to an extent sufficient to weaken the action of the adhesive on said section.

3. In a carton, the combination of a pair of inner flaps extending from opposite walls of the 15 carton and folded inwardly at the end of the carton, said flaps being cut away to provide a pouring opening, an intermediate flap extending from another wall of the carton and folded inwardly to overlie said inner flaps, said intermediate flap including a movable tab section normally overlying said opening, an outer flap extending from another wall of the carton and folded inwardly over the intermediate flap, said outer flap including a movable section normally 20 overlying the tab and the opening, and films of adhesive between the outer surfaces of said inner flaps and the inner surface of the intermediate flap, and between the outer surface of the intermediate flap and the inner surface of the outer flap, said movable section in the outer flap 25 lying offset upwardly from the surface of the intermediate flap to an extent sufficient to weaken the action of the adhesive on said section.

4. In a carton, the combination of a pair of inner flaps extending from opposite walls of the 30 carton and folded inwardly at the end of the carton, each flap having a cut-out with said cut-outs cooperating to form a pouring opening, an intermediate flap extending from another wall of the 35 carton and folded inwardly to overlie said inner flaps, said intermediate flap having a tab section held in place by readily destructible means, said tab section overlying said opening and portions of said inner flaps at one side thereof, 40 and an outer flap extending from another wall of the carton and folded inwardly to overlie said intermediate flap, said outer flap having a 45 movable section normally overlying said tab section.

5. In a carton the combination of a pair of inner flaps extending from opposite walls of the 50 carton and folded inwardly at the end of the carton, each flap having a cut-out with said cut-outs cooperating to form a pouring opening, an intermediate flap extending from another wall of the 55 carton and folded inwardly to overlie said inner flaps, a tab section in said intermediate flap defined by spaced weakened lines and a slit connecting the ends of said weakened lines and providing the free end of said tab section, said tab section overlying said opening with its free end 60 projecting beyond the edge of the opening and overlying said edge, an outer flap extending from another wall of the carton and folded inwardly to 65 overlie said intermediate flap and having a movable section normally overlying said tab section, and films of adhesive securing said intermediate flap to said inner flaps and said outer flap 70 to said intermediate flap.

6. In a carton, the combination of a pair of inner flaps extending from opposite walls of the 75 carton and folded inwardly at the end of the carton, each flap having a cut-out with said cut-outs cooperating to form a pouring opening, an

- intermediate flap extending from another wall of the carton and folded inwardly to overlie said inner flaps, a tab section defined at least in part by weakened lines terminating inward from the connection between the intermediate flap and the wall of the carton from which it extends, an outer flap extending from another wall of the carton and folded inwardly over said intermediate flap, said outer flap having a movable section normally overlying said tab section, and films of adhesive securing said intermediate flap to said inner flaps and said outer flap to said intermediate flap.
7. In a carton, the combination of flaps at one end of the carton extending from the walls of the carton and folded inwardly to close the end of the carton, said flaps including a pair of inner flaps formed with a pouring opening therethrough, an intermediate flap overlying said inner flaps and provided with a movable tab section normally overlying said opening and having a free end, said tab-section having a connection to its flap spaced inwardly from the connection of said flap to the wall from which it extends, and an outer flap overlying said intermediate flap and having a movable section normally overlying said tab section, said movable section in said outer flap extending inward from the free end of its flap with the end of said movable section lying substantially in registry with the connection of said intermediate flap to its wall, and films of adhesive securing said flaps in position.
8. In a carton, the combination of flaps at one end of the carton extending from the walls of the carton and folded inwardly to close the end of the carton, said flaps including a pair of inner flaps formed with a pouring opening therethrough, an intermediate flap overlying and secured to said inner flaps and provided with a movable tab section overlying said opening and having a free end defined by a slit, said intermediate flap being formed with a recess adjacent said slit to facilitate raising of said free end, and an outer flap overlying and secured to said intermediate flap and having a movable section normally overlying said tab section.
9. In a carton, the combination of flaps at one end of the carton extending from the walls of the carton and folded inwardly to close the end of the carton, said flaps including a pair of inner flaps formed with a pouring opening therethrough, an intermediate flap overlying and secured to said inner flaps and provided with a movable tab section normally overlying said opening and having a free end defined by a slit, said intermediate flap being formed with a recess adjacent said slit to facilitate raising of said free end, and an outer flap overlying a solid portion of said inner flaps, and an outer flap overlying and secured to said intermediate flap and having a movable section normally overlying said tab section.
10. In a carton, the combination of flaps at one end of the carton extending from the wall of the carton and folded inward to close said end, said flaps including a pair of inner flaps formed with a pouring opening therethrough, an intermediate flap overlying said inner flaps and having a tab section defined at least in part by a slit, and a second slit intersecting said slit first-mentioned, the free end of said tab section and the portions of said intermediate flap on either side of said second slit overlying a solid portion of said inner flaps, and an outer flap overlying and secured to said intermediate flap and having a removable section normally overlying said tab section.
11. In a carton, the combination of flaps at one end of the carton extending from the walls of the carton and folded inward to close said end, said flaps including a pair of inner flaps formed with a pouring opening therethrough, an intermediate flap overlying said inner flaps and having a pair of tab sections defined at least in part by slits, the free ends of both tab sections being defined by a single slit and the free ends of said tab sections overlying a solid portion of said inner flaps, and an outer flap overlying and secured to said intermediate flap and having a movable section normally overlying said tab sections.

CLARENCE J. ALFRED. 45
